UNITED STATES PATENT OFFICE.

ALONZO B. SEE, OF NEW YORK, N. Y., ASSIGNOR TO HIMSELF, AND WALTER L. TYLER, OF BROOKLYN, NEW YORK.

AUTOMATIC LOCK FOR ELEVATOR-DOORS.

SPECIFICATION forming part of Letters Patent No. 759,479, dated May 10, 1904.

Application filed February 23, 1904. Serial No. 194,648. (No model.)

To all whom it may concern:

Be it known that I, ALONZO B. SEE, a citizen of the United States, residing at the city of New York, in the borough of Manhattan and 5 State of New York, have invented certain new and useful Improvements in Automatic Locks for Elevator-Doors, of which the following is a full, clear, and exact description.

This invention relates to the automatic control of elevators, and has special reference to 10 a system of operation wherein the condition of the doors at the various landings determines whether the elevator can be moved or not.

15 There are various devices in existence for preventing an electrically-controlled elevator from being started until the door of the landing opposite which the elevator is standing has been closed. My invention is an improvement 20 on the known devices of this character intended primarily to avoid the faulty operation of the apparatus due to the shrinking or changing of shape or position of the landing-door upon which the apparatus is dependent 25 for its operation. The most common form of such device is a bolt mounted vertically near the swinging edge of the door, which when the door is closed springs into a socket in the door-frame and actuates a circuit-control- 30 ler therein, which thus puts the control-circuit of the elevator into operative condition, permitting the elevator to be moved away from the landing. On the arrival of the car at its destined landing the opening of the 35 door at that point again disables the control-circuit, preventing further movement of the car until the door is closed. It has been found in practice that by reason of the shrinkage or warping of the door, which, in private 40 residences especially, is usually of wood, throws the end of the bolt out of alinement with the socket in the frame, so that when the door is closed the control-circuit will not be put into operative condition and the elevator 45 cannot be moved. To avoid troubles of this character, I have resorted to the plan of placing the bolt in a horizontal position on the door and making it of such length as to extend substantially across its entire face

from the hinge edge to the swinging edge 50 and mounting it in suitable bearings fixed to the door in which it may slide freely toward and away from the vertical side of the door-frame. The bolt being of metal is not subject to shrinkage, its operative length 55 remains constant, and when it enters the cavity or socket in the door-frame it always projects the same distance thereinto and is always certain to actuate the circuit-controller. It may be added that in the shrinking of a door the 60 hinge edge remains fixed, while the swinging edge draws toward the hinge edge, thus opening a gap between the swinging edge and the door-frame. The vertical bolt before referred to being placed near the swinging edge 65 has a movement due to the shrinkage toward the hinges, and so gets out of line with its socket, whereas with the bolt arranged horizontally, as proposed by me, only the bearing for the bolt which is located near the 70 swinging edge partakes of this movement due to shrinkage, the bolt itself being unaffected.

75 My invention also comprises a lock to hold the bolt, preventing it from becoming displaced after it has once acted upon the controlling-circuit by the closing of the door. This lock is automatically released when the car approaches a landing, so that the bolt can be manually thrown to release the door and disable the control-circuit.

80 My invention will be described more in detail with reference to the accompanying drawings, in which—

85 Figure 1 is an elevation of part of an elevator-landing door and door-frame equipped with my improvements. Fig. 2 is a vertical section of the door, showing one side of the frame in elevation and a portion of the elevator-car. Fig. 3 is a horizontal section through the door and frame, taken just above 90 the horizontal bolt.

A represents a door at a landing in the elevator-shaft. It is hung in a frame B, its hinges being assumed to be located at the left-hand edge. Across the face of the door at about 95 the elevation where the door-knob usually occurs I mount a horizontal bolt C in bearings c and c', fixed to the door and in which it is

permitted to slide. The end of the bolt adjacent to the swinging edge of the door is beveled off, as shown at c^2 , like an ordinary door-latch, and the bolt is acted upon by an expanding spring c^3 , interposed between the bearing c and a collar c^4 on the bolt to normally force the beveled end of the bolt outward, the limit of such movement being determined by another collar c^5 . The bolt also carries a socket c^6 , engaged by the end of a crank d , pivoted to the door at d' and adapted to be swung to the left by either of the knobs d^2 to withdraw the end c^2 of the bolt. In the door-frame is arranged a box f , having its front plate flush with the frame and provided with an opening f' , through which the end c^2 of the bolt may enter. In this box is pivoted a spring-actuated circuit-controlling lever g , which is adapted to be struck by the end of the bolt when the latter enters the box and to be moved toward the rear wall of the box thereby. On the rear wall of the box are mounted two metal plates i and i' , forming the terminals of a circuit which may be understood to be the control-circuit of the elevator. These plates are adapted to be bridged and the circuit therefore closed when the lever g is pressed against them by the bolt C . The corner of the door-frame adjacent to the opening f' is provided with a curved or inclined surface k , over which the end of the bolt may ride and which forces it inward against the pressure of spring c^3 when the door is closed. On the vertical portion of the door-frame, to which the hinges are applied, I mount a vertical locking-rod o , which slides at its lower end through a bearing o' and is there formed with a number of shoulders o^2 , graduated in position and facing the end of the bolt C , any one of which will act as a stop for the end of the bolt, preventing it from sliding to the left. This rod may be held in its lower position, determined by a collar o^3 , either by gravity or a spring o^4 , in which position it serves as a detent for the bolt. The upper end of rod o is connected with a bell-crank p , pivoted at p' , and carrying at its opposite end a roller p^2 , which projects slightly into the elevator-shaft. The elevator-car is indicated by R , and to an upright portion thereof in the plane of the roller p^2 is fixed a cam r , adapted to strike the roller and swing it inward when the car passes and while the car is at a given landing to hold the roller in its depressed or inner position and the rod o consequently elevated from its normal position.

The operation is as follows: When the door is closed and the car distant from the landing, the end c^2 of rod C is projecting into the casting f and maintaining the control-circuit closed. It is locked in this position by the end of rod o , which stands behind the bolt C and prevents it from being moved to the left by turning the outside knob d^2 . When the car approaches a landing, the cam r strikes

roller p^2 and forces it inward, thus lifting the locking-rod o away from the end of the bolt C , in which position it is held while the car is at the landing. The person in the car then turns the knob d^2 and slides the bolt C to the left, which not only unlatches the door, but allows circuit-controlling lever g to disconnect the two terminals i and i' , and thereby disable the control-circuit of the elevator. The shifting of passengers or freight having been made the door must again be closed before the car can be started. Having closed the door, the bolt pushes lever g into contact with the circuit-terminals and the car is started. As soon as the cam r leaves the roller p^2 the locking-rod lowers to a position where one of its horizontal shoulders rests upon the end of the bolt, the corresponding vertical shoulder then standing immediately behind the end of the bolt and preventing any movement of the latter to the left. It will be seen that the series of graduated shoulders on the end of the rod provides for slight inaccuracies of construction or adjustment and at the same time permits the rod to move accurately to a locking position. If the rod had a squared end, it might strike on top of the bolt, and thus fail of its purpose. On the other hand, if the end of the rod was beveled similarly to the end c^2 of the bolt it would not be an efficient lock, since such a cam arrangement would permit either the rod or the bolt to move.

It will be seen that any change in the width of the door cannot affect the certainty of operation of the bolt, for its effective length remains constant notwithstanding such changes. The elevator having once left a landing cannot be interfered with by other would-be passengers who might try to open a landing-door, since all doors are locked until the car arrives at a given landing, when only the door at that landing can be opened.

Having described my invention, I claim—

1. The combination with an elevator-landing door, of a bolt mounted horizontally thereon and extending approximately across its entire face, a circuit-controller in the door-frame adapted to be actuated by said bolt, a lock for said bolt and means whereby the position of the elevator-car determines the condition of the lock.

2. The combination with an elevator-landing door, of a bolt mounted horizontally thereon and extending approximately across its entire face, a circuit-controller in the door-frame adapted to be actuated by said bolt, a lock for said bolt and means carried by the elevator-car for controlling said lock.

3. The combination with an elevator-landing door, of a bolt mounted horizontally thereon and extending approximately across its entire face, a circuit-controller in the door-frame adapted to be actuated by said bolt, a lock for said bolt consisting of a vertical rod adapted to be moved into and out of position behind

the bolt, a lever connected with said rod and a cam on the elevator adapted to actuate the lever.

4. The combination with an elevator-landing door, of a bolt mounted horizontally thereon and extending approximately across its entire face, a circuit-controller in the door-frame adapted to be actuated by said bolt, a lock for said bolt consisting of a vertical rod having a

series of graduated stops adapted to be presented to the end of the bolt.

In witness whereof I subscribe my signature in presence of two witnesses.
